(57) **CLAIM**

The ornamental design for a ski binding beam spring as shown and described.

DESCRIPTION

FIG. 1 is a perspective view of an embodiment of the claimed design in a closed position;
FIG. 2 is a top view of the claimed design of FIG. 1;
FIG. 3 is a bottom view of the claimed design of FIG. 1;
FIG. 4 is a front view of the claimed design of FIG. 1;
FIG. 5 is a rear view of the claimed design of FIG. 1;
FIG. 6 is a left-side view of the claimed design of FIG. 1;
FIG. 7 is a right-side view of the claimed design of FIG. 1;
FIG. 8 is a perspective view of an embodiment of the claimed design in a closed position;
FIG. 9 is a top view of the claimed design of FIG. 8;
FIG. 10 is a bottom view of the claimed design of FIG. 8;
FIG. 11 is a front view of the claimed design of FIG. 8;
FIG. 12 is a rear view of the claimed design of FIG. 8;
FIG. 13 is a left-side view of the claimed design of FIG. 8;
FIG. 14 is a right-side view of the claimed design of FIG. 8;
FIG. 15 is a perspective view of the claimed design of FIG. 1 in an open position;
FIG. 16 is a top view of the claimed design of FIG. 15;
FIG. 17 is a bottom view of the claimed design of FIG. 15;
FIG. 18 is a front view of the claimed design of FIG. 15;
FIG. 19 is a rear view of the claimed design of FIG. 15;
FIG. 20 is a left-side view of the claimed design of FIG. 15;
FIG. 21 is a right-side view of the claimed design of FIG. 15;
FIG. 22 is a perspective view of the claimed design of FIG. 8 in an open position;
FIG. 23 is a top view of the claimed design of FIG. 22;
FIG. 24 is a bottom view of the claimed design of FIG. 22;
FIG. 25 is a front view of the claimed design of FIG. 22;
FIG. 26 is a rear view of the claimed design of FIG. 22;
FIG. 27 is a left-side view of the claimed design of FIG. 22; and,
FIG. 28 is a right-side view of the claimed design of FIG. 22. The ornamental design which is claimed is shown in solid lines in the drawings. The broken lines in the drawings are for illustrative purposes only and form no part of the claimed design.
